By his Attorney,
Nelson R. Howard

UNITED STATES PATENT OFFICE.

HUGH R. HAMILTON, OF WEBSTER, MASSACHUSETTS, ASSIGNOR TO UNITED SHOE MACHINERY CORPORATION, OF PATERSON, NEW JERSEY, A CORPORATION OF NEW JERSEY.

FASTENER-INSERTING MACHINE.

Application filed July 20, 1926. Serial No. 123,788.

This invention relates to fastener-inserting machines and is illustrated as embodied in an eyeleting machine adapted for use in the manufacture of boot and shoes.

5 In the manufacture of boots and shoes it is common practice to use eyeleting machines having a single tool, comprising a tubular punch formed with a clenching surface, which acts as a combined punching and setting tool, first punching a hole through the work which is positioned for that purpose upon a suitable punch block, and then feeding the work to eyelet-inserting position where an eyelet is introduced by a tool having a spindle which picks the eyelet from the end of a race-way, transfers it to inserting position and forces it against a clenching surface formed upon the combined punching and setting tool thereby 10 15 20 25 30 35 40 45 50 55 60 65 70 75 80 85 90 95 100

clenching the eyelet in the work. In the operation of such a machine, the spindle of the set which picks the eyelet from the race-way and introduces it into the hole punched in the work by the combined punching and setting tool tends to force the chips punched from the work into the hollow interior of the tubular punch, the chips passing off, for example, through an outlet in the side of the punch. At times, however, there is an objectionable tendency for the chips to stick in the punch, and this has been particularly troublesome in the case of the setting of so-called oval eyelets, that is eyelets the cross-section of the barrel of which is elongated so that the area of contact between the edges of the chips and the inside of the punch is large relatively to the surface area of the chips and friction is correspondingly high.

It is an object of the present invention to provide an improved eyeleting machine organization having ejecting means arranged to force from the punch the chips punched from the work. In the illustrated machine an ejector is housed within the punch bar which carries at its lower end the combined tubular punching and setting tool and is normally held retracted so that it has no substantial engagement with the work during the punching operation. Means, however, is provided for thrusting the ejector forcibly forward relatively to the punching and setting tool at a period in the cycle of

operation of the machine after the completion of the punching operation so as to eject the chip from the punch.

With the above and other objects and features in view the invention will now be described in connection with the accompanying drawings and pointed out in the claims.

In the drawings,

Fig. 1 is a perspective view of a portion of the front of an eyelet-inserting machine embodying the present invention;

Fig. 2 is a vertical section through the mechanism of Fig. 1;

Fig. 3 is a perspective view and Fig. 4 is a side elevation of a detail of the upper end of the punch bar of the machine with the end of the ejector projecting therefrom.

The invention is disclosed herein as embodied in an eyeleting machine of the type disclosed in United States Letters Patent No. 686,928, granted Nov. 19, 1901, on an application filed in the name of Perley R. Glass. This is, however, merely for purposes of illustration, and it should be understood that the invention is not limited to use in connection with a machine of this type. Since many of the details of the machine form no part of the present invention and are not necessary for its understanding, they have been omitted from the drawings. For a showing of such parts of the machine reference may be had to said Letters Patent.

The illustrated machine is provided with a frame casting 10 carrying at its forward end a stationary rod 12 and bearings 14 in which is mounted for horizontal sliding movement a rod 16. Attached to rod 16 and slidably mounted on rod 12 is a head 18 provided with bearings 20 in which is mounted for vertical sliding movement a punch bar 22. Suitable mechanism may be provided, for example, as disclosed in said Letters Patent No. 686,928, for moving the sliding head 18 horizontally. Similarly suitable mechanism is provided for reciprocating punch bar 22 vertically in timed relation to the horizontal sliding movement of head 18. Thus punch bar 22 is moved downwardly to cause a combined punch and set 26 carried at its lower end to punch a hole through a work piece 28 positioned upon a

work support 30 which constitutes or is provided with a punch block. Then the pressure of the combined punching and setting tool 26 is slightly relieved by an appropriate upward movement of punch bar 22 and head 18 is slid to the left, as illustrated in Fig. 2, to feed the work to eyelet-inserting position. An eyelet is then picked from a raceway 32 by a spindle 34 of a lower setting tool 36 and is moved upwardly and introduced into the hole punched in the work. At this time the work is clamped against movement by a presser foot 38. As tool 36 moves upwardly, spindle 34 contacts with the lower end of the combined punching and setting tool 26 and is forced back into the lower setting tool 36 against a suitable compression spring, the lower set 36 forcing the eyelet up through the work and clenching it against the clenching surface of the combined punching and setting tool 26. After the eyelet has been clenched the punch bar 22 and tool 26 are moved upwardly away from the work support and then to the right, as viewed in Fig. 2, to complete the cycle of operation.

To get rid of chips 40 punched from the work by the combined punching and setting tool 26, in accordance with the present invention, an ejector 42 is housed within the punch bar 22 which is made hollow for this purpose. Ejector 42 is formed with a rigid collar 44 and projects upwardly, as shown at 46, through a plug 48 closing the upper end 38 of the hollow punch bar 22 and normally held in position by a pin 50 projecting through a J-shaped slot 52 in the side of the punch bar 22. A compression spring 54 is housed within the hollow punch bar 22 bearing at its lower end upon an internal shoulder 56 formed on the punch bar and at its upper end against collar 44 formed on ejector 42. A lighter spring 58 bears at its lower end against collar 44 and at its upper end against the lower end of plug 48, acting as a buffer and tending to prevent unnecessary slapping and noise. Carried by sliding head 18 is a bracket 60 having a horizontal portion 62 at its upper end carrying an adjustable stop screw 64 arranged in the path of movement of the upper end of ejector 42 as the punch and punch bar move upwardly after the clenching of each eyelet. During the punching and clenching operation ejector 42 is held retracted within the combined punching and setting tool 26 by spring 54, but when punch bar 22 moves upwardly after the eyelet has been set, the upper end 46 of ejector 42 hits the lower end 50 of stop 64 preventing further upward movement of the ejector, thereby compressing spring 54 and forcing the chips from the punching and setting tool 26 as the latter continues its upward movement with punch bar 22. Thus the chips are ejected after the

setting of each eyelet and before the setting tool is returned for the next punching operation.

Having described the invention, what I claim as new and desired to secure by Letters 70 Patent of the United States is:

1. A fastener-inserting machine having a combined punching and fastener-setting tool, means for introducing a fastener into a hole punched in the work by said tool co-operating with the tool to clamp the fastener in the work, an ejector within the said tool, means tending to retract the ejector, and means for causing the ejector to eject from the tool chips punched from the work. 80

2. A fastener-inserting machine having a combined punching and fastener-setting tool, means for introducing a fastener into a hole punched in the work by said tool co-operating with the tool to clamp the fastener in the work, an ejector within the setting tool, a spring tending to retract the ejector, and means for causing the ejector to eject from the tool chips punched from the work. 85

3. A fastener-inserting machine having a combined punching and fastener-setting tool, means for introducing a fastener into a hole punched in the work by said tool co-operating with the tool to clamp the fastener in the work, an ejector within the setting tool, a spring tending to retract the ejector, and means for moving the ejector lengthwise of the tool after the clenching of each fastener to eject from the tool chips 100 punched from the work. 90

4. A fastener-inserting machine having a combined punching and fastener-setting tool arranged to be moved into engagement with the work to punch a fastener-receiving 105 hole therein and then to be moved transversely to feed the work to fastener-inserting position, means for introducing a fastener into the hole punched in the work arranged to force the fastener against the 110 clenching surface of the setting tool thereby clenching the fastener in the work, an ejector within the setting tool, a spring tending to retract the ejector, and means for moving the ejector lengthwise of the setting tool after the clenching of each fastener to eject from the tool chips punched from the work. 115

5. A fastener-inserting machine having a combined punching and fastener-setting tool arranged to punch a fastener-receiving hole in the work and then to be moved transversely to feed the work to fastener-inserting position, means for introducing a fastener into the hole punched in the work 125 co-operating with the setting tool to clamp the fastener in the work, an ejector passing through the setting tool, a spring tending to retract the ejector, means for moving the tool and the ejector away from the work 130

after the clenching of each fastener, and a stop in the path of movement of the end of the ejector remote from the work arranged to be struck by the ejector, thereby ejecting 5 from the tool chips punched from the work.

6. A fastener-inserting machine having a punch bar, a combined punching and fastener-setting tool carried thereby and arranged to be moved into engagement with 10 the work to punch a fastener-receiving hole therein, means for introducing a fastener into the hole punched in the work co-operating with the setting tool to clench the fastener in the work, an ejector housed within 15 the punch bar and passing lengthwise through said bar and said tool, a spring tending to retract the ejector, and means for moving the ejector lengthwise of the tool to eject from the tool chips punched from the 20 work.

7. A fastener-inserting machine having a combined punching and setting tool arranged to be moved into engagement with the work to punch a fastener-receiving hole 25 therein and after the insertion of a fastener in the hole to be withdrawn from the work, an ejector positioned within said tool and having a portion extending away from the work, a spring tending to move the ejector 30 away from the work, and a stop positioned

in the path of movement of the portion of the ejector remote from the work and arranged when struck by the ejector to force the ejector outwardly through said tool to eject from the tool chips punched from the 35 work.

8. A fastener-inserting machine having a hollow punch bar, a combined punching and setting tool carried thereby and arranged to be moved into engagement with 40 the work to punch a fastener-receiving hole therein and after the insertion of a fastener in the hole to be withdrawn from the work, an ejector extending through said tool and punch bar and having a portion 45 projecting from the punch bar, a spring housed within the punch bar tending to move the ejector away from the work, and a stop positioned in the path of movement of the end of the ejector which projects 50 from the punch bar arranged when struck by the ejector during the movement of the tool away from the work to force the other end of the ejector outwardly through the tool to eject from the tool chips punched 55 from the work.

In testimony whereof I have signed my name to this specification.

HUGH R. HAMILTON.
